UNITED STATES PATENT OFFICE.

WILLIAM D. HARMON, OF MARYSVILLE, OHIO.

HARVESTER.

SPECIFICATION forming part of Letters Patent No. 519,019, dated May 1, 1894.

Application filed June 29, 1893. Serial No. 479,134. (No model.)

To all whom it may concern:

Be it known that I, WILLIAM D. HARMON, a citizen of the United States, residing at Marysville, in the county of Union and State 5 of Ohio, have invented a new and useful Harvester, of which the following is a specification.

My invention relates to improvements in harvesters and to that particular class thereof employed for harvesting corn.

The objects of the invention are to provide a machine adapted to be operated along one side of standing corn, to sever the same and carry it vertically to a common point where 15 it is conveniently held to be removed manually; to provide new and improved mechanism for accomplishing this function; to provide for a shocking device, whereby the corn may be conveniently stacked for shocking 20 and conveniently tied into shocks or bundles; and to provide for a convenient dumping of the shock thus formed and a square settling of the same firmly upon the ground; and to arrange or adapt for a utilization of 25 the driving power of the machine to the operation of the dumping mechanism both in the act of dumping and in the act of returning the parts to their normal position.

Various other objects and advantages of 30 the invention will appear in the following description and the novel features thereof will be particularly pointed out in the claims.

Referring to the drawings:—Figure 1 is a plan view of a harvester embodying my invention. Fig. 2 is a horizontal sectional view through the front end of the machine or the gathering device. Fig. 3 is a vertical longitudinal sectional view of the machine. Fig. 4 is a transverse sectional view through the 35 dumping tables. Fig. 5 is an inverted plan. Fig. 6 is a detail in perspective of the shocking post. Fig. 7 is a transverse sectional view through the shifting mechanism for operating the dumping tables.

Like numerals of reference indicate like parts in all the figures of the drawings.

In practicing the invention the framework may be constructed in various ways but is preferably constructed in the manner herein 40 shown and described, wherein as will be seen, I employ at opposite sides thereof pairs of lon-

gitudinal beams 1 and 2, the same being arranged parallel and the beams 1 being located at the outer sides. The beams 1 and 2 at the left side of the machine are of the same length 55 as the inner beam 2 is at the right side of the machine and the beam 1 at the right side of the machine terminates in rear of the front end of these beams. The entire series of beams is connected through the medium of transverse 60 beams 3, 4 and 5, and the whole supports the platform 6 which above the beams 1 and 2 at the left of the machine is cut away forming an opening 7, and at the right of the machine is likewise cut away at the front end thus 65 leaving the beam 2 at said side projecting in front of said platform. Resting partly on the platform at this front cut away portion and partly on the beam 2 that extends beyond the same at the right of the machine there is a 70 diamond-shaped frame 8, from the four angles of which posts 9, 10, 11 and 12 rise, and they in turn support an upper similar frame 13. At each side of the front post 9 of the series slotted bearing plates 14 are located 75 upon the bars of the frames 8 and 13, and set-screws 15 pass through the plates into the bars. These bearing-plates accommodate pairs of front vertical stub-shafts arranged 80 vertically opposite each other, the same accommodating sprocket-wheels 16. Metal plates 17 are located above and at the sides of the posts 10 and they are provided with sprocket-wheels 18, similar to those mentioned. In rear of the sprocket-wheels 18 85 shafts 19 are journaled in the frames 8 and 13 and extend above the upper frame and above each frame are provided with sprocket-wheels 20. A stub-shaft 21 is supported upon the platform within the frame 8 and carries upper and lower sprocket-wheels 22 and 23. Sprocket-chains 24 connect each upper and 90 lower series of sprocket-wheels 16, 18 and 20, that chain at the right passing around the lower wheels also passing around the idle 95 sprocket 22, so that the corresponding chain at the opposite side of the machine passes around the lower idle-sprocket 23. These chains are provided at intervals with pins 24, and upon each pin there is located a triangular catch 100 or hook 25. Guide-strips 26 are located within the sprocket-chains and against these said

chains ride, so that the said hooks are prevented from swinging beyond a right angle to the chain to which they are attached.

Upon the platform at the right side of the machine and extending parallel with the rear sides of the frames 8 and 13 is a pair of parallel guide-bars 27, which are connected by vertical posts 28. These bars 27 at their front ends project beyond the side angles of the frames 8 and 13, and at their rear ends project beyond the rear angles of said frames and at the latter ends are provided with lateral extensions 29 connected by a vertical bar 30. From the upper sides of the bars 27 at their front ends slotted plates 31 are secured by means of adjusting-screws 32. Vertical studs 33 are mounted on the plates and are provided with sprocket-wheels 34. In rear of the rear bar 28 a vertical shaft 35 is journaled in the horizontal bars 27 and above said bars are provided with sprocket-wheels 36, the two sets of sprocket-wheels being connected by sprocket-chains 37. Guide-strips are located at the inner sides of the sprocket chains, and triangular hooks are pivoted at intervals upon said chains.

At the opposite or left side of the diamond-shaped frame upper and lower frames 38 are located at the rear inclined sides of the frames 13, and vertical posts 39 serve to support the upper frame above the lower. Slotted bearing-plates 40 are made adjustable by set-screws 41 at the front ends of the frames 38, and stub-shafts 42 rise from the plates and carry sprocket-wheels 43. The rear angles of the frame 38 are occupied by sprocket-wheels, the outer wheels 44 being located upon a stub shaft 45 and the inner wheels 46 being mounted upon a vertical shaft 47. These wheels 46, 44, and 43 are connected by upper and lower endless chains 48 within which guide-strips 49 are located, as in the previous instance, and to which are secured pivotally triangular hooks 50 that ride against the strips and coact therewith in the manner heretofore specified. These frames 38 terminate slightly in advance of the extension 29 of the bars 27 so that they combine with said extension to form a passage. The chains being set in motion it will be seen that they will gather the stalks after they are cut and conduct them in a vertical manner through the two passageways 51 and 52 formed by the frames described to the points where the two passage-ways meet or intersect, from whence they will be caught by the hooks of the chains 48 and carried laterally to the short passage 53 formed by the rear end of the frames 38 and the extension at the rear ends of the bars 27. As the stalks make their exit from this passage-way 53 their upper ends are caught by an L-shaped arm 54 that projects from the outer side of the upper frame 38 and across said passage-way. A spring-arm 55 is mounted upon a stud 56 of the arm 54, and at its free end extends across the opening in the arm so as to form one side of the stalk-receiving frame or arm. It will

be obvious, however, that the accumulations of stalks deposited in the arm and retained by the spring may be readily removed from time to time by an attendant, the spring-arm yielding readily to a sufficient pressure.

A stub-axle 56 extends from the beam 1 at the right of the machine, and upon the same is mounted the ground-wheel 57. Bearing-standards 58 rise from the beams 1 and 2 at each side of the opening 7 of the platform and support a shaft 59 which accommodates a ground-wheel 60 that is located in said opening.

In suitable bearings 61 located upon the beams 1 and 2 a transverse main shaft 62 is journaled, one end of the main shaft, namely, that opposite the grain-wheel 57, being provided with a gear 63, which is driven by a gear 64 with which said shaft 59 is provided at one side of its center. The shaft 62 carries a small spur gear 65 and transmits its motion received from the shaft 59 to a short longitudinal shaft 66, which shaft 66 is journaled in depending bearings 67 upon the under side of the platform and is provided at its ends with beveled gears 68 and 69, the former meshing with the gear 65, and the latter meshing with a beveled gear 70, which is located upon the lower end of the short vertical shaft 21. At one side of the gear 65 a similar beveled gear 71 is mounted upon the shaft 62, and it meshes with a beveled gear 72 which is located upon the lower end of the rear vertical shaft of the side frame 38, which shaft has its lower end projected through the platform. Beyond this gear 71 a beveled gear 73 is located upon the shaft 62, and it engages with and drives a beveled gear 74 located upon the lower end of the rear shaft 35 of the opposite side frame. Thus it will be seen that motion is imparted from the grain wheel to the several guide or carrier chains heretofore described in a manner that will be obvious at a glance.

Below the forwardly projecting portion of the frame 8 a finger-bar 75 is supported, and in the same works an ordinary reciprocating harvester knife or cutter-bar 76, one end of which is by a pitman 77 connected to a crank-disk 78 located upon the front end of a short longitudinal shaft 79, which is journaled in bearings 80 upon the under side of the platform to the left of the carrier-mechanism. The rear end of this shaft has a beveled-gear 81 which receives its motion from and meshes with a gear 82 mounted upon the main transverse drive-shaft 62.

The platform of the machine terminates above the rear transverse beam 5, but the longitudinal beams 1 and 2 project rearward beyond the same to support the dumping-table. The rear ends of these beams 1 and 2 are connected in pairs by short transverse bars 83 and each has secured thereto a curved standard 84 in which is mounted a swiveled caster-wheel 85, which supports the rear end of the machine. Between the two inner beams 2 it

will be seen that nothing intervenes, so that the framework is open from the rear transverse beam 5 to a point between the caster-wheels. This portion of the framework is covered by the sectional sliding-table 86 which surmounts the beams 1 and 2. The table-sections are provided upon their under sides with inverted T-shaped slides 87, and the same are engaged by keepers 88 located transversely opposite each other, and upon the upper sides of the beams 1 and 2. Thus it will be seen that the table-sections may be slid together to form a solid platform or table or separated so that their inner ends or edges are vertically opposite the inner beams 2. Rack-bars 88 are secured to the under sides of the table-sections and extend transversely, and their teeth are engaged by gear-wheels 89 located upon longitudinal shafts 90 at opposite sides of the machine and supported in bearings between the opposite pairs of beams 1 and 2. One shaft 90 terminates immediately in advance of the transverse beam 5, though the one at the right extends up to the main transverse shaft 62. However, each is provided in front of the transverse beam with a beveled gear 91, and the two gears intermesh with beveled gears 92 which are located upon a short transverse shaft 93 journaled in bearings 94 located upon the inner longitudinal beams 2. The front end of that shaft 90 at the front of the machine is provided with a beveled gear 94 immediately at the rear of the shaft 62, and upon this shaft 62 opposite an opening formed in the platform and in front of said shaft 90 a sleeve 95 is located, said sleeve being fixed. At each side of the sleeve upon the shaft loose conical shells 97 are located, and at the inner ends of the shells beveled gears 96 are located, each shell and gear being adapted for movement loosely upon the shaft. Conical friction pulleys or gears 98 are located at the outer side of each shell, and mounted upon a splined grooved sleeve 99. These grooved sleeves are engaged by the terminals of an inverted U-shaped shifting-frame 100 made fast to a sliding bar 101 which surmounts the platform 6 at one side of the opening 102 in which the shifting-frame is mounted and is provided with slots 103 at its ends through which guide bolts 104 pass into the platform 6 and serve to guide the bar 101 in its movements. A lever 105 is fulcrumed as at 106 upon the platform at the side of the bar, and by a link 107 is connected with the bar in a loose manner. A lever 108 is pivoted as at 109 to the platform in rear of the slide-bar 101, and the rear end of said lever projects into the path of pins 110 located upon the front edge of the sliding table section at the right side of the machine, so that as the section is slid outward or inward, said pins will contact with the rear end of the lever and operate the same and inasmuch as the front end of said lever engages with the sliding bar 101 said sliding-bar will be operated in a similar manner and direction, and

thus cause the friction pulleys to be moved out of contact with the conical friction shells 97. The outward movements of the table-sections are also limited by stop-pins 111 that extend upward from the beams 1 and from the under sides of the table-sections. 70

In bearings 112 located upon the stationary platform 6 and the short transverse beams 83 75 there are pivoted the opposite ends of swinging strips 113 which serve to condense the lower end of the shock and prevent the same from following the movements of the tail-sections. When the machine is being operated, 80 the hinged strips 113 lie flat upon the platforms and hence do not offer obstructions, over which the operators would be liable to trip while placing the stalks in position thereon. They are, however, as will hereinafter 85 appear, swung to a vertical position when it is desired to condense the bottom of the shock or bundle, and serve to force the stalks from the sections as the same are slid. A vertical post 114 rises from the rear center of the 90 platform 6, and is suitably braced; and is surmounted at its upper end by a cup or basket 115 designed to receive a ball of binding-cord for tying shocks. Transverse metal cleats 116 are secured to the back face of the 95 post 114, and vertical guide rods 117 connect the ends of said cross-cleats 116 and form vertical ways. A cast-metal head 118, of crescent shape, is secured to the inner end of a horizontal arm 119, and at its terminals has perforations 120, which receive and loosely ride upon the guide-rods 117. A coiled spring 121 is secured at its upper end to the transverse cleat 116, and at its lower end to a part that moves with the horizontal arm 119, the 100 tendency of the spring being to normally elevate the arm. The horizontal arm is surmounted by a pair of curved arms 122 which are pivoted as at 123 at their inner ends and overlap each other. A pivoted trigger 124 is 105 located in a slot immediately in rear of the curved arm, and the lower end of the trigger is loosely connected with the front end of a reciprocating rod 125 whose rear end is adapted to bear against and ride over a cam 126 110 formed upon the post 114 and is sprung against the same by a coiled spring 127 coiled upon the rod 125. When not influenced by the spring but by the cam the trigger remains elevated at its upper end in rear of the crossed 115 or overlapping inner ends of the curved arms, thus locking them in their outward position, but when the horizontal arm together with the curved arms is lowered and the rod is influenced only by the spring the said rod is 120 retracted and draws the trigger downward out of the path of the curved arms permitting them to fold or swing into alignment with the horizontal arm, and thus in a manner herein-after obvious be readily disengaged or withdrawn from the shock. 125

This completes the construction of the machine, and the operation of the same is as follows:—The machine is drawn along the side of

a body of standing corn, the team being located at the left of the machine and connected with the draft-tongue 130. The corn is divided by the diamond-shaped frames at the center of the same and a portion deflected to each side of said frames where the stalks are gradually concentrated and severed even with the platform 6. As they are severed they are caught by the hooks of the inwardly traveling chains in the manner heretofore described and carried back through the passages 51 and 52 to the passage 53, where they are caught by the arm 54. An attendant grasps the corn by the armful and deposits the same against the curved arms of the shock-post around which the shock is formed, the butts of the stalks resting upon the table sections which of course are closed. When a sufficiently large shock is produced, the same is tied, and the lever 105 is swung to the left or away from the grain-side of the machine. Through the gears described motion is conveyed to the longitudinal shafts which are rotated and through the medium of their gears communicate motion to the rack-bars upon the under sides of the table-sections, so as to spread or separate the same. The hinged strips are swung upward by hand so as to prevent the stalks following the movements of the table-sections, and the latter being drawn from under the lower end of the shock, said shock is dropped solidly and squarely upon the ground so as to stand firmly. The dropping of the shock causes the horizontal arm of the shocking-post to descend against the tension of its supporting-spring so that the shock is maintained intact until it reaches the ground. The opening or separating of the table sections is arrested by the pins 110 operating against the lever, which as before stated, causes a breaking of contact between the cone-pulley and the shell. When this has been accomplished the operator shifts the lever 105 so as to throw the opposite cone-pulley and shell into engagement and reverse the movements of the shafts and gearings, the machine all the while being driven along and thus the table-sections are closed or drawn inward. The descent of the horizontal arm of the shocking-post serves to unlock the curved arms of the post, and as the machine is driven off the curved arms yield or swing into alignment with the horizontal post and are thus drawn readily from their engagement with the shock. In this manner the operation is continued the shocks being formed and deposited with facility and dispatch.

From the foregoing description in connection with the accompanying drawings it will be seen that I have provided a machine of comparatively simple construction, that may be readily operated, and which will sever and gather the corn-stalks in a convenient manner for bundling, and which will facilitate the building of the shock and tying of the same, and finally that after such tying the

movement of the machine may be utilized to drive the gearing for purpose of dumping the shock squarely upon the ground, and that an automatic disengagement of the shocking-devices will then occur.

Various changes in the details of construction will readily suggest themselves to those skilled in this class of machines, and I therefore do not limit my invention to such details as I have herein shown, but hold that I may make such variations as may suggest themselves from time to time and yet be within the scope of my invention.

Having described my invention, what I claim is—

1. In a corn harvester, the combination with a platform, a cutting mechanism, and means for operating the same, of a central angular frame located at the front end of the platform and provided at its outer angles with sprocket wheels, chains passing around the wheels at opposite sides of the frame and provided with stalk-engaging projections, opposite side diverging straight frames surmounting the platform and combining with the central frame to form intermediate passages leading to a common exit in rear of the central frame extending beyond the side angles of the central frame, sprocket wheels located on the ends of side frames, and sprocket-chains arranged upon the wheels and provided with stalk engaging projections, and means for operating said wheels, substantially as specified.

2. In a corn harvester, the combination with a platform, a cutting mechanism, and means for operating the same, of a central angular frame located at the front end of the platform and provided at its side angles with sprocket wheels, chains passing around the wheels at opposite sides of the frame and provided with stalk-engaging projections, opposite side straight diverging frames surmounting the platform and combining with the central frame to form intermediate passages leading to a common exit in rear of the central frame and extending beyond the same, sprocket wheels mounted on the side frames, and sprocket chains arranged upon the wheels and provided with stalk-engaging projections, a lateral extension for one of the side frames located in rear of the central frame at the point of meeting between the two passages, and a stalk-receiver arranged at the end of said extension, and means for driving the wheels, substantially as specified.

3. In a corn harvester, the combination with the platform, of a diamond-shaped frame, an intermediate shaft having upper and lower sprocket wheels located upon the platform, a drive shaft, and connections between the same and the sprocket wheel carrying shaft, sprocket wheels at the opposite side angles of the diamond shaped frame, endless sprocket chains engaging the wheels at the sides and front of said frame, and the sprocket wheels of the intermediate shaft, stalk-engaging projections carried by the sprocket

chains, opposite side guide frames arranged parallel to the rear sides of the diamond frame and combining therewith to form passages communicating at a point in rear of the diamond frame, sprocket-wheels carried by said side guide frames, sprocket chains mounted on the wheels and having stalk-engaging projections, mechanism between the drive shaft and the sprocket wheels for operating the latter, a lateral extension for the guide frame leading from the point of intersection of the two passages, and an L-shaped arm located at the end of said passage and having an opening at one side covered by a yielding spring-arm, substantially as specified.

4. In a corn harvester, the combination with an upper and a lower diamond shaped frame projecting over the front of the platform, front and rear pairs of sprocket-wheels arranged vertically opposite each other, upper and lower endless chains having triangular pivoted hooks arranged on the chains, and guides at the inner sides of the chains, of the opposite diverging upper and lower bars, intermediate vertical bars, the same combined with the rear bars of the diamond frames to form passages, sprocket wheels at the opposite ends of the upper and lower diverging bars, endless chains connecting the sprocket wheels, triangular hooks carried by the chains, and guards arranged at the inner sides of the chains, the lateral extension bars extending from one set of diagonal bars, the L-shaped arm extending from the other set of diagonal bars, the spring arm secured to the L-shaped arm and extending across the opening thereof, and means for operating the sprocket wheels, substantially as specified.

5. In a corn harvester, the combination with a supporting framework having an opening at its rear end, of separable horizontally-slidable table-sections arranged to cover said opening, means for operating the table-sections, and swinging strips supported by the framework slightly above the plane of the table-sections to hold the lower ends of shocks from movement with the sections, substantially as specified.

6. In a corn harvester, the combination with the framework having an opening at its rear end, the opposite table-sections mounted for sliding over the opening, the rack-bars 88 secured to the under side of said sections, the longitudinal shafts 90 journaled in the bearings in the framework and having gears 89 engaging the rack-bars, an intermediate shaft 93 having gears 92, and the gears 91 mounted on the shaft 90 and engaging the gears 92, of the keepers arranged on the framework, inverted T-shaped slides 87 arranged under the table sections and in the keepers, the drive wheel, the transverse drive shaft 62, means for communicating motion from said wheel to said shaft, a beveled gear on the front end of one of the shafts 90 and adjacent to the shaft 62, beveled gears arranged upon the shaft 62 at opposite sides of

the beveled gear of the shaft 90, and means for shifting either of said beveled gears of the shaft 62 into engagement with the beveled gear of the shaft 90, substantially as specified.

7. In a corn harvester, the combination with a framework having an opening in its rear side, the opposite slidable table sections, the rack-bars thereunder, the longitudinal shafts 90 under the table sections, gears 89 upon said shafts and engaging the rack bars, the intermediate shaft 93 having end gears 92, the gears 91 arranged on the shafts 90 and engaged by the gears 92, of the ground-wheel, the main transverse drive shaft 62, means for communicating motion from the ground wheel thereto, the opposite hollow cones 97 having beveled gears at their inner ends and arranged to slide upon the shaft 62, the beveled gear 94 on the end of one of the shafts 90 and located between the beveled gears 96, the opposite sleeves arranged at the outer ends of the hollow cones 97, cone pulleys carried by the sleeves, a shifting lever, and devices between the lever and the sleeves for operating the latter, substantially as specified.

8. In a corn harvester, the combination with the framework having an opening at its rear end, the opposite slidable table sections, the rack-bars thereunder, the longitudinal shafts 90, the gear wheels 89 arranged thereon and engaging the rack bars, the intermediate transverse shaft 93, gear wheels 92 on the ends of said shaft, the gear wheels 91 on the shafts 90 engaged by the gear wheels 92, of the drive wheel, the transverse drive shaft operated thereby, the beveled gear 94 arranged on the end of one of the shafts 90 adjacent to the shaft 62, the opposite hollow cones 97 arranged on the shaft 62 at opposite sides of the gear 94, gear wheels at the inner ends of the hollow cones, the outer cone pulleys arranged in the hollow cones and mounted upon reciprocating sleeves, the superimposed slide-bar arranged on the framework, the yoke depending from the slide-bar and engaging the sleeves, the lever fulcrumed at one side of the slide-bar, and the link connected to the lever and to the slide-bar, substantially as specified.

9. In a corn harvester, the combination with the framework having an opening at its rear end, the opposite slidable table-sections, the rack bars thereunder, the longitudinal shafts 90, the gear wheels 89 arranged thereon and engaging the rack bars, the intermediate transverse shaft 93, the gear wheels 92 on the ends of said shaft, the gear wheels 91 on the shafts 90 engaged by the gear wheels 92, of the drive-wheel, the transverse drive-shaft operated thereby, the beveled gear 94 arranged on the end of one of the shafts 90 adjacent to the shaft 62, the opposite hollow cones 97 arranged on the shaft 62 at opposite sides of the gear 94, gear wheels at the inner ends of the hollow cones, the outer cone pulleys arranged in the hollow cones and mounted upon reciprocating sleeves, the superimposed slide-bar arranged on the framework,

- the yoke depending from the slide-bar and engaging the sleeves, the lever fulcrumed at one side of the slide-bar, the link connected to the lever and to the slide-bar, projections 5 arranged on one of the table-sections, and devices for operating the slide-bar adapted to be struck by the projections on the table-sections and arranged between the same and the slide-bar, substantially as specified.
10. In a corn harvester, the combination with the framework having an opening at its rear end, the opposite slideable table-sections, the rack-bars thereunder, the longitudinal shafts 90, the gear-wheels 89 arranged thereon and engaging the rack-bars, the intermediate transverse shaft 93, the gear wheels 91 on the ends of said shaft, the gear-wheels 91 on the shafts 90 engaged by the gear-wheels 92, of the drive wheel, the transverse drive shaft 20 operated thereby, the beveled gear 94 arranged on the end of one of the shafts 90 adjacent to the shaft 62, the opposite hollow cones 97 arranged on the shaft 62 at opposite sides of the gear 94, gear wheels at the inner ends of the 25 hollow cones, the outer cone pulleys arranged in the hollow cones and mounted upon reciprocating sleeves, the superimposed slide-bar arranged on the framework, the yoke depending from the slide-bar and engaging the 30 sleeves, the lever fulcrumed at one side of the slide-bar, the link connected to the lever and to the slide-bars, pins arranged on the front edge of one of the table-sections, and a toggle-lever having its members pivoted upon 35 the framework and arranged in the path of the pins and at its opposite end engaging loosely with the slide-bar, substantially as specified.
11. In a corn harvester, the combination 40 with the framework, the stationary platform and the rear separable table-sections, of a shocking post rising from the stationary platform, an arm horizontally disposed and mounted movably upon and at a right angle 45 to the shocking post, a spring for supporting the arm, and pivoted short arms arranged on the horizontal arm, substantially as specified.
12. In a corn harvester, the combination 50 with the framework, the stationary platform, and the rear separable table-sections, of the vertical shocking post, the horizontal arm

mounted movably thereon and at a right angle thereto, a spring for supporting said arm, a pair of pivoted arms arranged on the horizontal arm, means for locking the same at an angle to the horizontal arm when the latter is raised, and for automatically unlocking the same and permitting them to swing into alignment with the horizontal arm when the latter is lowered, substantially as specified. 60

13. In a corn harvester, the combination with the framework, the stationary platform, and the rear separable table-sections, of the shocking post extending upwardly from the rear edge of the platform, a vertically movable horizontal arm arranged upon and extending at a right angle from the shocking post, a pair of curved pivoted arms arranged upon the horizontal arm and overlapping each other at their inner ends and beyond their 70 pivots, a pivoted latch mounted in a slot in the horizontal arm and taking in rear of the curved arms, a reciprocating rod mounted in supports under the horizontal arm and loosely pivoted at its rear end to the latch, a spring 75 for normally pressing the arm toward the shocking post, and a cam arranged on the shocking post and adapted to be ridden by the end of the rod, substantially as specified.

14. In a corn harvester, the combination 80 with the framework, the stationary platform, and the rear separable table-sections, of a shocking post rising from the platform, upper and lower cleats secured to the rear face of the shocking post, vertical guide-rods connecting the ends of the cleats, a horizontal arm, a casting on the inner end of the same having perforations for the reception of the guide-rods, a suspension spring for the arm, curved pivoted arms arranged on the horizontal arm, and means for locking them in a transverse position, and means for automatically liberating the curved arms at a lowering of the horizontal arm, substantially as 90 specified. 95

In testimony that I claim the foregoing as my own I have hereto affixed my signature in the presence of two witnesses.

WILLIAM D. HARMON.
